UNITED STATES PATENT OFFICE.

GEORGE W. WERUM, OF MARSHALLTOWN, IOWA.

ABSTRACT TITLE AND METHOD OF FORMING THE SAME.

Application filed September 11, 1923. Serial No. 662,055.

To all whom it may concern:

Be it known that I, GEORGE W. WERUM, a citizen of the United States, residing at Marshalltown, in the county of Marshall 5 and State of Iowa, have invented certain new and useful Improvements in Abstract Titles and Methods of Forming the Same, of which the following is a specification.

The invention has for an object to effect improvements in the means for establishing title to motor vehicles, to the ends that the steps necessary will be simplified and the possibility of false evidence of ownership minimized. It is an important aim 10 of the invention to provide means whereby the preparation of certificate of title by a state official, and the making of a permanent state record thereof may be simplified, and the two made co-active in novel 15 ways. Thus, in simplifying the procedure, it is to be considered that for the permanent record in the State office, such as that of a commissioner of automobiles, a comparatively small entry memorandum is sufficient, 20 but on the certificate of title, it is usually desirable to have more information, and it has also been found desirable to have attached thereto blanks to enable the transfer of title from the original holder of the certificate 25 to another. It is a purpose of the invention, therefore, to enable the use of certificates of title which will be coordinated with certain blanks of a permanent record book in a novel way, which will simplify the 30 construction of the book itself without requiring an excessive content of sheets, while at the same time attaining the advantages of arrangements which would involve a much greater number of elements and bulk, 35 as well as expense in the preparation of a permanent record.

Additional objects, advantages and features of invention reside in the structural details, arrangement and combination of 40 elements, as will be understood more clearly hereinafter from the description and the accompanying drawings, in which,

Figure 1 is a representation of a sheet of a record book,

Fig. 2 is a similar view of a certificate of title, of the same width as the book page, coordinated therewith, as will be more particularly pointed out,

Fig. 3 is a view of the back of the title sheet.

There is illustrated in Fig. 1, a book page

10, having a series of entry areas 11 thereon each extending the full width of the page and occupying such vertical space thereon as may be required for the information which 60 is considered essential for the complete record. Ordinarily, this would include spaces for data peculiar to each car, such as the trade name, type and serial number of the car, the engine number and its horse power and number of cylinders, the year made, its weight as equipped at the time of completion and any other information which may be required. In addition, the date of registration, name of the owner, name of vendor and the endorsement of the registrar or other official issuing the certificate may 65 be involved. In Fig. 2, there is shown a certificate of title sheet, the upper part of which is provided with a space having 70 blanks for the same uses and identically arranged with the blanks on the area units 11 of the record book. The areas 11 of the record book are separated by lines 12 which have a definite space relation to the blanks thereunder, and the top of the page should have a similar relation to the blanks in the upper section. Blanks on the certificate sheet are similarly arranged with respect to 75 the top of the sheet, and at each upper corner of the sheet there are printed identical serial numbers 18, below and inwardly of which there are lines of perforation intersecting each other and extending to the side and top of the sheet respectively which will 80 enable the detachment of the numbers as desired. The area within the perforations is gummed on the back. At the top of the sheet the words "Abstract number" are 85 printed, with arrows pointing laterally in each direction to indicate the numbers 18. This sheet may be printed in ornamental 90 form if desired and may be of a distinctive color or paper and should be saliently distinguished by a legend such as "Certificate 100 of title" in a location which will not be objectionable in the use of the blanks.

Various ideas as to the data to be required in the book and on the certificate may be embodied, or some already known form these may be adopted, as desired, and I do not regard the invention as limited in these particulars, except as claimed.

The blanks in the book may provide for entry of liber and page of records of mortgages or other papers affecting title, and similar provision on the back of the title

sheet, as shown in Fig. 3. Similarly, where annual car licenses are issued independently of the certificate of title, entries of the license numbers from year to year may be provided for. By this method, the application for license will be greatly simplified, as it would only be necessary to ask for license for a car as entered in abstract of a given number. An economy in paper and clerical work would thereby be effected. When issuing a new license under this arrangement, the license is made out from the data in the abstract, and operation of a numbering machine stamp will be all that is required to indicate on the abstract that a license has been obtained for the current year, and show its number.

In the use of the devices, the issuance of the certificate may be provided by law, or regulation by the proper authorities, requiring the presentation of a bill of sale, conditional or otherwise, to secure the issuance of the certificate, and this evidence may be required to be accompanied by an application blank having the essential data.

When the necessary evidence and data are presented to the recording and issuing authority, one of the certificate sheets is taken, to be laid with its upper part in registry with a section 11 of the recording book. The serial number 18 which will lie at the outer edge of the page is moistened on the back and pasted down upon the face of the book page with the sheet correctly alined with the page. This secures upon the page sufficiently to prevent its casual disturbance while the necessary entries are being made. A carbon sheet is then inserted between the two, and the certificate filled out, the record being accomplished by the same operation. When the certificate is filled out, its removal will leave the number 18 adhering to the page, and the entry thereon will thus be automatically numbered to coincide with the number of the certificate, obviating liability of error in entering data of a certificate of one number upon blanks having a different number in the record. This work may readily be accomplished by the use of book typewriters. By requiring notice of all mortgages or other transactions affecting title, these may be entered on the abstract and on the certificate so that a complete showing of title may be effected at all times.

This arrangement permits the printing and making up of a book having only the

sheets containing the essential permanent abstract data to be kept in the record, while the certificates may be printed separately and kept stacked in the order of the numbers 18, ordered from the top downward, and using these in their order, the entries on the record book will be numbered likewise, and only as the certificates are issued.

Any certificates which may be lost or stolen from the record office before being duly filled in, will not have corresponding numbers in the record, and missing numbers may be reported to the police for apprehension of persons presenting them. The mere existence of a certificate without corresponding number in the record will ordinarily be evidence of fraud.

This method will also be an aid in police work, generally, as, when it is desired to hold a given person who is a motorist, on telegraphic order, the giving of his certificate number will be a ready means of identifying him. The presentation of any certificate without a serial number will impair its value, and either a duly authorized or certified restoration or a new certificate should be obtained under such circumstances.

The validity of any certificate may be established by reporting the number and asking for information thereon, so that if any person erases one name and substitutes another on a certificate, the fraud may be quickly discovered. A telegram of about ten words with the main facts would convey this information from the State officials to an inquirer, so that a low cost for such investigation would be involved.

What is claimed is:—

1. In a device of the character described, in combination a record book page having appropriately designated spaces for the entry of certain data, a certificate sheet having similar blanks adapted to be alined with those of the page, and having a detachable numbered part coated with adhesive connected to the sheet body by marginal weakened material and arranged to be detached in a predetermined form by separation of the certificate from the page to which it is attached thereby.

2. A structure as set forth in claim 1 in which the said detachable numbered parts are duplicated at opposite sides of the sheet.

In testimony whereof I have affixed my signature.

GEORGE W. WERUM.
